HYDROSTATIC PRESSURE RELEASE MECHANISM

John C. Goff, 1007 Copley Lane, Silver Spring, Md.

Filed Sept. 29, 1950, Ser. No. 187,650

11 Claims. (Cl. 102—13)

(Granted under Title 35, U.S. Code (1952), sec. 266)

This invention relates generally to means for selectively releasing a slack length of mooring cable from a buoyant marine mine and more specifically to a new and improved depth regulating device similar to that set forth in the copending application of Joseph D. Turlay for a Depth Regulating Device for a Moored Mine, Serial Number 465,931, filed November 17, 1942, now Patent No. 2,706,948, and adapted for releasably maintaining a bight in a portion of the mooring cable adjacent the mine until the latter has risen within the water to a preselected depth of submergence whereupon the reduction in the tension upon the mooring cable as the bight is released causes the cable drum within the mine's anchor to lock and thereby in this manner secure the cable, and accordingly the mine attached thereto, within the water at a preselected depth of submergence.

The depth regulating and cable release mechanism of the present invention is adapted to be employed with mines released from a launching craft above the surface of the water or from the torpedo tube of a submarine operating submerged or afloat, as the case may be, and with the mine and anchor, launched as a unit and separating as they descend through the water with the interconnecting cable therebetween paying out from a supply drum in the anchor as the more buoyant mine rises toward mooring position at a selected depth below the surface of the water.

As the mine anchor falls away from the mine during the downward movement thereof within the water, the pull of the anchor against the cable causes the hydrostatic depth regulating and releasing device connected thereto to be withdrawn from a recessed portion of the mine's anchor whereupon the pull of the mine against the mooring cable at this time is applied across a pair of detachable pull pins opposingly arranged and forming a part of the depth control release mechanism and about which a relatively short length of cable hereinbefore referred to as the bight is connected. Connected to one end of this bight preferably by a short length of cable is the mine and to the other end thereof the upper end of the mooring cable to which is fastened the mine's anchor. As the bight is released by the disengagement of the pull pins from the release mechanism responsive to a preselected setting of the hydrostatic element of the latter, the momentary decrease in tension in the mooring cable is effective in this manner to produce a locking action upon the cable supply reel disposed within the anchor, now resting upon the bed of the body of water, to prevent further paying out of the cable from the reel to accordingly thereby secure the mine at a preselected depth below the surface.

Whereas, cable release and depth regulating devices of this type heretofore devised are generally designed to respond to hydrostatic pressures between 30 and 90 pounds in accordance with selected positions of adjustment made thereon during assembly, changes in naval tactics now require that such mechanisms operate with ranges of between 30 to 500 pounds and with further provision there-

in for making such pressure responsive adjustments in the field if necessary, to conform more accurately to the conditions of launching and location wherein the mines are to be planted.

In order that these requirements may be met, the cable release of the present invention provides an improved arrangement for controlling the pressure response of the hydrostatic element thereof and accomplished by the provision therein of a cantilever spring arrangement varying in cross section and adjustable selectively in length to provide a pressure range heretofore unobtainable by mechanisms of comparable size employing helical springs and capable of performing the same mechanical work.

It is an object of the present invention to provide a new and improved means for releasing a bight in the mooring cable of a submarine mine when the mine has risen to a predetermined depth of submergence within the water.

Another of the objects is to provide a new and improved cable release device adapted to be armed by a predetermined pressure thereon and released by a predetermined pressure of less value than the arming pressure.

A still further object is to provide a new and improved cable release mechanism wherein a bight in a mooring cable of a moored mine is released as the mine rises to a preselected depth beneath the surface of the water.

An additional object is to provide a new and improved cable release mechanism wherein the response of the hydrostatic element thereof is controlled by the adjusted effective spring length of a cantilever beam and the range of response of the mechanism is greatly extended beyond the range of prior art devices.

Other objects and many of the attendant advantages of this invention will be readily appreciated as the same becomes better understood by reference to the following detailed description when considered in connection with the accompanying drawings wherein:

Fig. 1 illustrates in diagrammatic form the launching and mooring of a submarine mine employing the device of the present invention;

Fig. 2 is a cross sectional view of the cable release device of the present invention in an initial condition;

Fig. 3 is a plan view of the release device shown in Fig. 2 with the cover removed and in release pin securing position;

Fig. 4 is a plan view of the device of Figs. 2 and 3 with the cover removed and the pins released therefrom;

Fig. 5 illustrates in diagrammatic form the cable release device of the present invention as connected in the mooring cable of the mine;

Fig. 6 illustrates in diagrammatic form the mine mooring cable after the release of the bight therein, the cable release mechanism having fallen away;

Fig. 7 is a cross sectional view taken along line 7—7 of Fig. 2;

Fig. 8 is a cross sectional view taken along line 8—8 of Fig. 2;

Fig. 9 is an end view in elevation of the linkage as viewed along the line 9—9 of Fig. 2;

Fig. 10 is a fragmentary sectional view illustrating the plunger of the release mechanism in latched position; and

Fig. 11 is a fragmentary sectional view illustrating the plunger of the release mechanism in released position.

Referring now to the drawings and more particularly to Fig. 2 thereof the cable release mechanism of the present invention generally designated 5 is shown therein to include an annular cup shaped housing member 6 over which is secured as by screws 7 a circular cover plate 8 adapted by means of an O ring gasket 9 interposed therebetween to provide a watertight closure for the housing.

Arranged somewhat off center within the housing 6 and movable axially within a vertical guide bore 10 provided therefor in a rectangular formed block portion 11

projecting upwardly from the housing base 13, Fig. 2, is a piston 14 adapted to provide an operative connection between a cable release mechanism generally designated 15 and a hydrostat assembly generally designated 16 and including an elongated pressure tank 17 secured as by nuts 18 to depending lugs 19 preferably formed integral with the under surface of the housing 6.

Centrally secured about the lower end of the piston 14 as by a self locking nut and washer 20 and 21 respectively, is a flexible diaphragm member 22 formed preferably from rubber or like material and clamped as by a ring screw 23 about the outer periphery thereof within a threaded opening provided therefor in the upper surface of the pressure tank 17. As the diaphragm is thereafter deflected inwardly responsive to a predetermined hydrostatic pressure being applied to the outer surface thereof, the piston 14 centrally secured to the diaphragm is moved thereby downwardly within a guide bore 24 provided therefor in the base section of the tank 17 with the upper end 25 of the piston moving away from the release mechanism 15, arranged within the housing, and thereby to perform an arming operation upon the release mechanism, the significance of which will become more clearly apparent as the description proceeds. An annular plate 27 arranged between the ring screw 23 and diaphragm 22 and clamped with the diaphragm to the tank 17 extends inwardly to within close but spaced adjacency with respect to the piston 14 thereby to provide a protective cover for the diaphragm for the purpose of preventing possible damage occurring thereto during assembly of the device or the subsequent mounting or withdrawal thereof from the casing of a mine during the planting operation.

Inverted over an inclined surface 28 provided therefor upon the upper surface of the tank 17 and secured thereto as by screws 29, Fig. 8, is an elongated U-shaped channel member 30 thereby forming upon the tank an enclosure hereinafter referred to generally as the spring housing 31 and wherein is secured to the end of the tank 17 as by clamping members 33 and 34 respectively, a cantilever spring 35. In order that this spring possess the physical characteristics for producing in the device the wide pressure response required thereof, the spring 35 is preferably tapered in form with a gradually increasing cross section beginning at or near the point of securement thereof as by screws 36 to the end of the tank 17, Fig. 2, to a thickened end portion 37 projecting outwardly from the end of the housing 31 and wherein is provided in the spring an elongated slot 38 suitable for receiving therethrough the piston 14. A block member 39 interposed between the spring and housing 6 and suitably secured to the piston as by pinning thereto at 41 initially deflects the spring 35 to the extent of causing the latter to maintain the block firmly against the under surface of the housing 6, the block 39 further providing for positioning the piston 14 properly with respect to the release mechanism 15 operatively associated with the upper end of the piston, as illustrated in Fig. 2.

Depending from the under surface of the block 39, as viewed in Fig. 2, and adapted for being received within the slot 38 formed therefor in spring 35 is a finger 42 adapted to position the block 39 so that a fulcrum surface 43 thereupon is maintained in the manner indicated, across the spring 35 and whereby the spring is deflected downwardly by this surface as the piston 14 responds to the inward deflection of the diaphragm 22 as will result by the device being submerged the required depth within a body of water.

Movable longitudinally over the spring 35 as by an adjustment screw 49, is a fulcrum assembly generally designated 45 and comprised of a rectangular block member 46 wherein is arranged, as illustrated in Fig. 2, a pair of opposingly spaced rollers 47 adapted for movement within suitably formed tracks 48 preferably milled in the inner surface of the tank and channel members 17 and

30 respectively, Fig. 7. For the reason that the tracks 48 are arranged parallel to the respective upper and lower surfaces of the spring 35 the rollers 47 are maintained by the tracks in bearing contact with these respective surfaces during movement thereover of the fulcrum 45 irrespective of the tapered nature of the spring.

Provided on the adjustment screw 49 is a square end section 50 suitable for receiving thereover a wrench or like tool, not shown, whereby the screw may be rotated 10 by the tool for shifting to selected positions of adjustment the fulcrum member 45 along the surface of the spring. An extending flange 52 preferably formed integral with the screw 49, Fig. 2, providing, together with the square end section 50 thereon, a structure suitable 15 for rotatably securing the screw to the tank whereby the fulcrum may be shifted thereby in either direction along the surface of the spring without the separation of the screw from the retaining surfaces provided therefor between the block and tank members 34 and 37 respectively.

20 As the position of the fulcrum member 45 is shifted along the spring 35 the deflectable length of the latter is altered selectively to conform to that indicated by a pointer 53, Fig. 7, carried by the fulcrum and movable, by way of an elongated slot 55, across a scale 56 secured as by screws 57 to the sidewall section of the channel member 30. The scale is so calibrated as to indicate in feet, or the equivalent thereof, the depth of submergence within a body of water required to deflect the diaphragm 22 of the hydrostat against the opposing force 30 of the adjusted spring 35 whereby the piston 14 is thereby carried by the diaphragm to a second position effective to operate the release mechanism to armed position as will become more clearly apparent as the description proceeds.

35 Since the deflection of a cantilever beam of uniform cross section under a constant load varies inversely with the cube of the length thereof between the fulcrum and the point of load application, varying the position of the fulcrum will accordingly vary the load required for a 40 constant deflection of the beam in a cube relation whereas, in the present device, adapted for operation in response to a constant deflection of the beam the tapering of the spring 35 increases this relation to a quartic curve or higher thereby to provide a cable release having a 45 far greater range of pressure response than heretofore possible with apparatus previously devised and capable of performing the same mechanical work.

The purpose of the arming operation being performed 50 upon the device and which is accomplished by movement of the piston 14 by the diaphragm of the hydrostat from an initial position to a second position as hereinbefore indicated, assures proper submersion of the mechanism before it can be operated to bight releasing position thereby preventing premature operation of the 55 device before the mine is properly planted. After having been properly submerged the mechanism is operated to bight releasing position responsive to the return of the piston to its initial position as will hereinafter be more fully described.

60 The release mechanism 15 comprises a pair of release or pull pins 60 made annular in form for closely fitting within bores 61 provided therefor in the side wall section of the housing 6 as illustrated in Fig. 3 and with a moisture proof seal being provided about the pins and the 65 housing as by O-ring gaskets 62 conventionally arranged within grooves provided therefor in the pins and disposed for bearing contact with the inner surface of the bores 61.

Mounted within the housing 6 for rotation about a pair of vertically disposed pins 63 is a pair of locking members 70 64 adapted at 65 for registering engagement with annular grooves 66 provided therefor in the inner ends of the release pins 60 and whereby the pins are secured by these members to the housing concurrently with securing there- 75 to the sections of the mooring cable 67 and bight 58 secured to the ends of the pins 60 as by ring members

68. Rotation of the locking members 64 into locking engagement with the release pins 60 is accomplished by movement outwardly from the block member 11 of a rectangular plunger 69 slideably fitted within a way or groove 70 provided therefor in the upper surface of the block, Fig. 3, with the plunger being therein so retained as by a cover plate 71 fastened to the block by screws 72.

The plunger 69 is connected, as illustrated in Fig. 9, with the locking members 64 by way of coordinating links 73 through which pins 74 and 75 extend to be thereafter secured therethrough as by cotter keys 76. A continuous spring 77 arranged about the pins 74 and with the ends thereof overlaying the outer edge of the lower links 73 provides an arrangement whereby an initial biasing force is applied by the spring to the links 73 in a direction for causing them to rotate about the pins 74 and toward the plunger 96, Fig. 4, thereby to become effective to release the locking members 64 from their engagement with the release pins 60 upon movement of the plunger 69 from the block 11 during the releasing operation of the device as will become more apparent as the description proceeds.

The locking members 64 are moved inwardly into locking engagement with the grooves 66 provided therefor in the release pins by movement into the block 11 of the plunger 69 which operates to rotate the locking members about their respective points of pivot and into engagement with the grooves 66 concurrently with cocking the spring 77 as the links 73 are extended outwardly to the position illustrated in Fig. 3.

Vertically disposed to the side of the block member 11 and rotatably mounted within a drilled stud provided therefor, but not shown, in the base of the housing 6 and within a cylindrically formed guide 80 extending upwardly from the outer surface of the cover plate 8 is an arming shaft 81 having formed integrally therewith an extension hereinafter referred to as the safety arm 82. A second arm 83 hingedly secured as at 84 adjacent the lower end section of the shaft 81 is arranged for horizontal movement within a slotway 85 provided therefor in the block 11 as illustrated to advantage in Fig. 2.

The plunger 69, upon movement inwardly into the guide surface 70, is secured in this inward position by downward movement thereover, and through which the shaft extends, of a locking lug 86 adapted to be seized by a latch equipped end 87 of the plunger as the locking member 64 are rotated thereby into engagement with the annular grooves 66 in the release pins 60. The locking lug 86 when in this locking position over the latch 87 rests substantially upon the end of the piston 14, Fig. 2, and initially with the safety arm 82, so disposed above an extending flange section 88 on the lug that lifting of the lug from the latch is thereby prevented until such time as the arm is rotated from the flange to lug releasing position, Fig. 4, as accomplished by the withdrawal of the arming pin 93 from the arming shaft 81.

The initial position of the safety arm 81 above the flange 88 places the lower arm 83 outwardly within the groove 85, as illustrated in Fig. 2, with a biasing force being applied to the arm in the direction for causing movement thereof toward the piston 14 by the connection therewith of a spring 89 extended between the end of the arm 83 and a lug 90, Fig. 3, projecting upwardly from the base of the housing 6.

The operation of the cocking or arming the mechanism following the assembly thereof is accomplished by the insertion of a bar or like tool within an opening now shown closed as by a cap screw 79 and thereby to apply sufficient force to the extended end of the plunger 69 as to urge it inwardly into the block 11 to the position for allowing the locking lug 86 to descend over the latch equipped end 87 of the plunger. The lug 86 is urged downwardly over the latch by the arrangement over the lug of a helical spring member 91 interposed between

the upper end of the lug and the cover plate 8 wherein the spring is retained.

The locking of the lug 86 in plunger securing position, as indicated in Fig. 2, is accomplished by a wrench or like tool being applied to the square end section 92, Fig. 3, of the arming shaft 81 to rotate the shaft to the position for moving the arm 82 above the flange 88 of lug concurrently with the alignment of horizontally drilled openings provided therefor in the guide and shaft members 80 and 81 respectively whereby there may be inserted therewithin an arming pin 93 for maintaining the shaft 81 against further rotation until the pin is subsequently extracted therefrom during the launching operation of the mine.

15 The release device, to which are secured the ends of the mooring cables 67 and bight 58, is arranged within a recess provided therefor, but not shown, between the mine 94 and anchor 96 and adapted for being withdrawn from this recess as the anchor falls away from the mine during the downward descent of the mine and anchor within the water following the launching of the mine as hereinbefore described. The release device 5 by being secured in close adjacency to the mine, Fig. 5, an arming wire 95 secured to the arming pin 93 and in a manner 20 not shown to the anchor 96, operates to withdraw the pin from the mechanism as the more buoyant mine moves a preselected distance from the anchor, Fig. 1, during its ascent toward the surface of the water.

25 The releasing of the shaft 81 by the withdrawal of the arming pin 93 therefrom causes the rotation of the arm 83, as drawn by the spring 89, to a position against the side of the piston shaft 14, Fig. 10, whereupon as the pressure against the outer surface of the diaphragm 22 becomes sufficient to overcome the force exerted upon 30 the piston by the spring 35 the piston is carried downwardly by the diaphragm from its position against the undersurface of the lug 86 sufficiently for allowing the spring 89 to draw the arm 83 beneath the lug to the position indicated in Fig. 11. This operation completes 35 the arming of the mechanism effective, as hereinbefore described, to insure proper submergence of the mine within a body of water before the device can thereafter be operated to bight release position.

40 As the mine 94 rises within the water following the arming thereof the resultant lessening in the hydrostatic pressure against the diaphragm 22 to a value sufficient to allow the spring 35 to lift the piston 14 whereby the end of the piston is thereby brought to bear against the under surface of the arm 83 causing a lifting of the arm and accordingly the block 86 from latching engagement with the plunger 64, Fig. 11. When this occurs, the piston has completed a cycle of operations and the plunger snaps to retractive position, Fig. 4, by the urge of spring 77 causing the rotation of the latching members 64 from engagement with the pins 60 whereupon the pins are drawn by the mooring cable 67 free of the housing 6 allowing the mechanism 5 to fall from the cable, Fig. 1. The release of the bight or slack loop 58 produces a momentary interruption in tension in the mooring cable required to cause 45 locking of the cable supply reel, not shown, disposed within the anchor and now resting upon the bed of the body of water.

50 Obviously many modifications and variations of the present invention are possible in the light of the above teachings. It is therefore to be understood that within the scope of the appended claims the invention may be practiced otherwise than as specifically described.

55 The invention described herein may be manufactured and used by or for the Government of the United States of America for governmental purposes without the payment of any royalty thereon or therefor.

60 What is claimed as new and desired to be secured by Letters Patent of the United States is:

65 1. A device for releasing a bight in the mooring cable of a submarine mine including, in combination, a hy-

drostat, a bight release mechanism, a piston movable by said hydrostat, means in engagement with and movable by said piston sufficiently to operate said release mechanism to bight releasing position as the piston is moved a predetermined amount by hydrostat pressure applied to the hydrostat, a cantilever spring arranged for opposing movement of said piston by said hydrostat, and settable means movable along the surface of said spring to change the effective length of the spring thereby to selectively vary the opposition of said spring to said movement of said piston.

2. A device for releasing a bight in a mine cable including, in combination, a hydrostat, a piston movable by said hydrostat, a release mechanism operatively connected to said piston and responsive to a predetermined movement thereof to effect the release of said bight, a cantilever spring disposed for resisting the movement of said piston by said hydrostat, and means movable over the surface of said cantilever spring for selectively varying the effective spring length thereof thereby to control the depth at which the hydrostat is effective to cause release of said bight.

3. A device for releasing a bight in a mine mooring cable including, in combination, a movable piston, a bight release mechanism including a movable element in engagement with said piston and responsive to a predetermined degree of movement thereof to effect the release of said bight, means including a hydrostat for applying said movement to the piston, a cantilever spring disposed for yieldably opposing movement of said piston by said hydrostat, an adjustable fulcrum moveable to different settings along the surface of said spring respectively corresponding to different depths at which the bight is to be released thereby to alter selectively the opposition of said spring to movement of said piston.

4. An underwater device for releasing a bight in the mooring cable of a submarine mine including, in combination, a piston, a hydrostat responsive to the pressure of the surrounding water to effect movement of said piston, a release mechanism operatively connected to said piston and responsive to a preselected cyclical movement thereof to effect the release of said bight, a cantilever spring secured at one end and disposed for deflection by movement of said piston, a fulcrum movable adjustably over said spring to vary selectively the portion thereof deflectable by said piston, and means forming a part of said fulcrum for opposing reverse deflection of said spring between said fulcrum and said secured end thereof.

5. A device of the character disclosed for releasing a bight in a mine mooring cable including, in combination, a housing, a pair of release pins operatively connecting said cable at the ends of said bight, releasable means including a latch for releasably securing said pins to said housing and responsive to a release of said latch to release said bight, a hydrostat, a piston movable by said hydrostat from an initial position to an armed position responsive to a predetermined increase in hydrostatic pressure applied to said hydrostat, a tapered cantilever spring fixedly secured at the smaller end thereof and disposed for deflection at the other end by movement of said piston as the piston is moved to said armed position, a pair of tracks carried by said hydrostat and arranged on opposite sides of said cantilever spring and parallel to the upper and lower surfaces thereof respectively, an adjustment screw, a fulcrum member arranged for bearing contact upon the said surfaces of said spring and movable thereover by adjustment of said screw to alter selectively the deflectable length of said spring, and means responsive to movement of said piston to said armed position to release said latch upon the return of said piston to said initial position by said spring in response to a reduction in hydrostatic pressure applied to the hydrostat.

6. An underwater device of the character disclosed for releasing a bight in a mooring cable for a subfloating mine including, in combination, a housing, a pair of release pins connected respectively at the ends of a length of said cable, means including a latch for releasably securing said pins to said housing thereby to form a bight in said cable, a block carried by said housing and movable for engaging said latch for maintaining said securing means in pin securing position, biasing means for effecting movement of said securing means to pin releasing position upon disengagement of said block from said latch, a piston, a hydrostat responsive to a predetermined hydrostatic pressure of the surrounding water to effect movement of said piston from a first position to a second position, a cantilever spring disposed for yieldably opposing movement of said piston by said hydrostat and to return said piston to said first position upon a predetermined decrease in said hydrostatic pressure upon the hydrostat, and means responsive to movement of said piston to said second position to effect the disengagement of said block from said latch upon return of said piston to said first position thereby to release said bight of cable.

7. A device of the character disclosed for releasing a bight in a mine mooring cable including, in combination, a housing, a pair of release pins operatively connecting in said cable the ends of said bight, releasable means including a latch for releasably securing said pins to said housing in response to the release of said latch to release said bight, a hydrostat, a piston movable by said hydrostat from an initial position to an armed position in response to a predetermined increase in hydrostatic pressure applied to said hydrostat, a cantilever spring disposed for opposing movement of said piston by said hydrostat, a fulcrum member movable adjustably over said spring to selectively control the opposition thereby of said piston movement, and means responsive to movement of said piston to said armed position to release said latch upon the return of said piston to said initial position.

8. A device of the character disclosed for releasing a bight in a mine mooring cable including, in combination, a housing, a pair of release pins operatively connecting in said cable the ends of said bight, releasable means including a latch for releasably securing said pins to said housing and responsive to the release of said latch to release said bight, a diaphragm, a second housing enclosing one side of said diaphragm, a piston movable by said diaphragm from an initial position to an armed position in response to a predetermined hydrostatic pressure applied to the unclosed side of said diaphragm, a cantilever spring disposed for opposing movement of said piston by said diaphragm and movable to return said piston to said initial position upon a predetermined decrease in said hydrostatic pressure, and means responsive to movement of said piston to said armed position to release said latch upon the return of said piston toward said initial position.

9. A device of the character disclosed for releasing a bight in a mine mooring cable including, in combination, a housing, a pair of release members operatively connecting in said cable the ends of said bight, releasable means including a latch for releasably securing said members to said housing and responsive to a release of said latch to connect in said cable said bight, a piston, a hydrostat responsive to a predetermined hydrostatic pressure for moving said piston from an initial position to an armed position, a cantilever spring disposed for moving said piston from said armed position to said initial position upon a predetermined reduction in said hydrostatic pressure applied to said hydrostat, and means responsive to movement of said piston from said initial position to the armed position to release said latch as the piston is returned to said initial position by said spring.

in response to a reduction in said hydrostatic pressure applied to the hydrostat.

10. An underwater device of the character disclosed for releasing a bight in the mooring cable of a subfloating mine including, in combination, a housing, a pair of release pins removably arranged within said housing and connected respectively to said cable and the ends of said bight, securing means including a latch for releasably securing said pins to said housing, a block movable for engaging said latch for maintaining said securing means in said pin securing position, biasing means for effecting movement of said securing means to pin releasing position upon disengagement of said block from said latch, a piston, a hydrostat responsive to a predetermined hydrostatic pressure of the surrounding water to effect movement of said piston from a first position to a second position, a cantilever spring disposed for deflection by movement of said piston from said first position, a pair of tracks arranged on opposite sides of said spring parallel to the under and upper surfaces thereof respectively, an adjustment screw, a fulcrum arranged for bearing contact with the said surfaces of said springs and movable thereover by adjustment of said screw thereby to alter selectively the deflectable length of said spring, and means responsive to movement of said piston to said second position to effect the disengagement of said block from said latch upon return of said piston to said first position by said spring in response to a reduction in the hydrostatic pressure applied to the hydrostat.

11. An underwater device of the character disclosed for releasing a bight in a mooring cable for a subfloat-

ing mine including, in combination, a housing, a pair of release pins removably arranged within said housing and connected respectively to said cable and to the ends of said bight, means including a latch for releasably securing said pins to said housing, a block movable for engaging said latch for maintaining said securing means in said pin securing position, biasing means for effecting movement of said securing means to pin releasing position upon disengagement of said block from said latch, a piston, a hydrostat responsive to a predetermined hydrostatic pressure of the surrounding water to effect movement of said piston from a first position to an armed position, a cantilever spring disposed for deflection by movement of said piston from said first position, a pair of tracks arranged on opposite sides of said spring and parallel to the respective upper and lower surfaces thereof, an adjustment screw, a fulcrum member movable by said screw along the surface of said spring, a multiplicity of rollers carried by said fulcrum member and disposed for bearing contact respectively with the surfaces of said spring and movable in said tracks by adjustment of said fulcrum member by said screw, and means responsive to movement of said piston to said armed position to effect the disengagement of said block from said latch upon the return of said piston to said first position.
